UNITED STATES PATENT OFFICE.

CHARLES P. SCHLEGEL, OF ROCHESTER, NEW YORK, ASSIGNOR TO SCHLEGEL MANUFACTURING COMPANY, OF ROCHESTER, NEW YORK, A CORPORATION OF NEW YORK.

ROBE-STRAP.

1,202,229.

Specification of Letters Patent.

Patented Oct. 24, 1916.

Application filed March 8, 1916. Serial No. 82,944.

To all whom it may concern:

Be it known that I, CHARLES P. SCHLEGEL, of Rochester, in the county of Monroe and State of New York, have invented certain new and useful Improvements in Robe-Straps; and I do hereby declare the following to be a full, clear, and exact description of the same, reference being had to the accompanying drawings, forming a part of this specification, and to the reference-numerals marked thereon.

My invention relates to a strap and more particularly to a robe supporting strap and has for an object to provide a strap readily attachable to various forms of supports for holding robes and the like.

A further object of the invention is to provide a strong, durable, and serviceable robe supporting strap of novel construction particularly designed for use upon the backs of automobile seats.

To these and other ends the invention consists in certain improvements and combinations of parts, all as will be hereinafter more fully described, the novel features being pointed out in the claims at the end of the specification.

In the drawings: Figure 1 is a view illustrating one of the completed straps embodying the invention; Fig. 2 is a view illustrating the manner of applying the first winding of cord material upon the end securing members for connecting the same; Fig. 3 illustrates the manner in which a layer or filler of cord material is wound or wrapped upon the winding shown in Fig. 2; Fig. 4 is a view illustrating the manner of braiding the cover over the filler illustrated in Fig. 3, and Fig. 5 is an enlarged detail sectional view taken through the end of one of the completed straps.

Similar reference numerals throughout the several views indicate the same parts.

The present invention is particularly adapted for use upon the backs of automobile seats in supporting different kinds of robes or wearing apparel, but is equally adaptable for use in other locations as will be readily understood.

Referring more particularly to the drawings, 10 represents any suitable support to which the strap 11 may be attached. The strap comprises a pair of end securing members 12 and 13 preferably in the form of

links, the latter of which carries an extension plate 14 provided with holes 15 adapted to receive suitable screws for connecting the securing member to the support 10, while the former is adapted to be removably connected with a catch 16 which is also mounted upon the support 10 as shown in Fig. 1. The strap is formed by passing a cord or series of cords, but preferably a single strand of any suitable material, through the securing members 12 and 13 to form a plurality of windings 17, as indicated in Fig. 2, the respective ends of the cord being tied or otherwise secured upon the links. A filler in the form of a covering for the windings preferably comprises strands or threads 18 wound or wrapped around the windings and preferably in a direction at right angles to said windings as indicated in Fig. 3, but any other suitable filler material may be used if desired. In this way I produce a strap body 75 substantially circular in cross section and embodying a certain degree of softness and resiliency which is found desirable in an article of this kind. After the strands or cords 18 have been wrapped upon the windings 17 I provide a cover 19 of suitable fabric material which is preferably braided over the entire body of the strap including the end securing members in a manner indicated at 20 in Fig. 4, the cover being left unfinished to more clearly illustrate the method of applying the same over the windings or wrappings 18. When the braiding of the cover has been completed the ends which extend over the securing members 12 and 13 80 are unraveled at opposite sides along the outer edges of the links to the inner ends of the same. The strands upon one side of the link are then cut short and turned inwardly as indicated at 21 in Fig. 5. The remaining 85 uncut strands are folded over the cut strands as indicated at 22. A thread 23 is wound around the strap to secure the strands 22 as shown in Fig. 5. An end cover is then crocheted or otherwise formed over and secured upon the ends of the braided cover as illustrated at 24, thereby forming a completed strap of neat and attractive appearance for supporting various articles of wearing apparel. By winding a cord upon the end securing members in the manner indicated in Fig. 2 a very strong construction is formed, 90 the windings 17 serving to carry the weight 95

of the articles placed upon the strap without causing any stretching or straining of the material forming the cover, while the filler or wrappings 18 give body and resiliency to the strap. The cover being formed of a seamless tubular fabric is free from ridges which would be objectionable in a strap of this kind.

The strap may have both ends permanently secured to the support 10, but is preferably arranged with one end removably connected thereto, in order to better facilitate the placing upon or removal from the strap of the wraps or other garments.

15 I claim as my invention:

1. A strap comprising a pair of securing members connected by a series of windings of cord material, a seamless cover, a filling material between said windings and cover, and end covers for the strap mounted upon the ends of the seamless cover.

2. A strap comprising a pair of spaced loops connected by a series of windings, a cover over said windings divided at each end into two parts, one of which is folded

through the loop upon the other, and means for securing said folded ends.

3. A strap comprising a pair of spaced loops connected by a plurality of windings, a cover over said windings of greater length than the latter and divided at its ends, said divided portions being folded upon the windings, one over the other, and means for securing the divided portions upon said windings.

4. A strap comprising a pair of spaced loops connected by a body of flexible material, a cover over said body and end covers connected with the loops and adapted to receive the ends of the body cover.

5. A strap comprising spaced securing members, an inner body connecting said securing members, an outer body upon the inner body, a covering upon the outer body and end covers secured upon said body covering.

CHARLES P. SCHLEGEL.
